BOTTLE CARRIER

Edwin L. Arneson, Morris, Ill., assignor to Morris Paper Mills, Chicago, Ill., a corporation of Illinois

Application December 17, 1951, Serial No. 261,936

7 Claims. (Cl. 220—113)

The present invention relates to an improvement in 15 flexible paperboard article carriers of the automatic set-up type.

It is an object of the invention to provide an improved partition structure for a paperboard bottle carrier of the type which automatically attains an erected 20 and locked condition upon movement of its walls to a spread, erected condition, the partition structure having novel provision to accommodate movement of certain bottom forming panels of the carrier to an interlocked condition.

More specifically, it is an object of the invention to provide an improved flexible paperboard carrier having opposed pairs of side and end wall panels, bottom forming panels hinged to the bottom margins of those panels and hinged to one another so as to constitute an 25 automatically erecting bottom, and a multiple-ply partition hinged at its opposite ends to one pair of the walls and extending parallel to the other pair of walls in the erected condition of the carrier, this partition terminating adjacent the bottom of the carrier to afford full depth bottom protection and having improved provisions to permit unimpeded movement of the bottom panels to locked position.

It is a further object of the invention to provide an 40 article carrier forming blank of paperboard or similar material which is generally rectangular in shape and which is cut and creased to provide integrally connected side and end wall forming panels, bottom wall forming panels and cross partition forming panels, the opposite edges of the side and end wall panels being defined by parallel 45 crease lines extending transversely of the blank in longitudinal spaced relation, the bottom forming panels extending along one side edge of the blank and being integrally connected to the side and end wall forming panels along a crease line extending longitudinally of the blank, certain of the bottom forming panels being provided with 50 diagonal crease lines defining at one end thereof bendable laps for connection with the adjoining bottom forming panels, integral extensions on the other ends of the side wall forming panels having angularly related crease lines dividing the same into cross partition forming panels and triangular connecting panels, and at least one of the cross partition forming panels having a length in the longitudinal direction of the blank which is approximately 55 the same as the depth of the side wall forming panels and having a diagonal crease line adjacent the bottom forming end thereof.

The foregoing statements are indicative in a general 60 way of the nature of the invention. Other and more specific objects will be apparent to those skilled in the art upon a full understanding of the construction and operation of the carrier.

A single embodiment of the invention is presented for 65 purpose of illustration. The invention may be incorporated in other modified forms coming equally within the scope of the appended claims.

2

In the drawings,

Fig. 1 is a top plan view of a flexible paperboard blank used in the production of the improved carrier;

Fig. 2 is a fragmentary top plan view showing the blank following an initial gluing operation and indicating in broken line a subsequent fold of certain parts of the blank;

Fig. 3 is a top plan view illustrating the condition of the blank after the further fold referred to above, with further adhesive applied thereto;

Fig. 4 is a top plan view of the carrier blank after still another folding operation has been performed thereon, also indicating the application of adhesive thereto prior to a final folding operation;

Fig. 5 is a top plan view of the carrier in completed, knocked-down condition;

Fig. 6 is a top plan view of the carrier in a partially erected condition, showing the manner in which the vertically extending partition of the carrier accommodates movement of the automatic bottom forming panels as the latter shift toward fully and locked erected condition;

Fig. 7 is a top plan view of the finally erected carrier, showing the bottom forming panels in interlocked relation; and

Fig. 8 is a view in vertical section along a line corresponding to line 8—8 of Fig. 7.

The advantages of an automatically erecting bottom structure in flexible paperboard bottle carriers and like cartons are universally recognized. An example of such an automatic bottom arrangement is illustrated and described in the patent to Parks et al. 2,011,232 of August 13, 1935, and also in the patents to Himes, 2,273,266 of February 17, 1942, and Lebold, 2,389,318 of November 20, 1945.

It is the purpose of this invention to make these advantages available in a bottle carrier having a medial, full depth partition or divider which extends downwardly almost to the bottom of the carrier and, lacking the improvement of the invention, would impede automatic movement of the bottom forming panels to erected and locked position.

Referring to Fig. 1 of the drawings, the blank 10 from which the improved carrier is fabricated comprises a pair of similar wall sections 11, 12, each including an end wall and a side wall panel. The sections are integrally articulated to one another by a vertical crease 13. This crease defines one end of a side wall panel 14 of section 12 and the opposite end margin of the panel 14 is defined by a vertical crease 15. An end wall panel 16 is integrally hinged to panel 14 by a crease 15.

The carrier wall section 11 comprises an end wall panel 17, similar in size and shape to panel 16, which is hinged to side wall panel 14 by crease 13. A further side wall panel 18, corresponding in size and shape to panel 14, is integrally hinged to end wall panel 17 by a crease 19. Side wall panel 18 has a glue lap 20 integrally hinged thereto by a crease 21.

A horizontally extending crease 22 defines the bottom margin of the respective sections 18, 17, 14, 16. This crease serves to integrally hinge to the wall panels certain bottom forming panels, as follows: Bottom panel 23 is hinged to side wall panel 18, bottom panel 24 is hinged to end wall panel 17, bottom panel 25 is hinged to side wall panel 14, and bottom panel 26 is hinged to end wall panel 16. Panels 23 and 25 have diagonal creases 27, 28, respectively, which serve to hinge thereto the glue lap elements 29, 30, respectively. Panels 23 and 25 are specially shaped to serve as components of an automatic bottom construction, and the flaps 24, 26 have inclined side margins for the same purpose. This type of automatic bottom construction is well-known, being

exemplified in the Parks et al., Himes and Lebold patents noted above, so that further extended description thereof is superfluous.

Each of the carrier sections 11, 12 is provided with a suspending and vertical partition unit, that associated with the section 11 being generally designated 31 and that associated with the section 12 being generally designated 32. Inasmuch as these units are, in general, similar to one another, only the unit associated with carrier section 11 will be particularly described, on the understanding that similar parts and relationships in the unit 32 are designated by corresponding reference numerals, primed.

Unit 31 comprises a grip element 33 which is separated from side wall panel 18 by a horizontal slit 34. It is integrally hinged to a triangular upper extension 35 of panel 18 by means of a vertical crease 36. Element 33 is provided with a U-shaped slit 37 and a horizontal crease 38 joining the ends of the slit, thus to provide a handhole which is normally covered by a pivoted flap 39, in a well-known manner.

A foldable triangular gusset or connecting member 40 is integrally hinged by an angular crease 41 along the hypotenuse of the triangular upper extension 35, and a horizontal crease 42 in turn integrally hinges this foldable member 40 to a relatively large partition and suspending panel 43 which is of generally rectangular outline. Panel 43 is integrally hinged to the grip element 33 by means of a crease 41a which is, in effect, an aligned extension of crease 41. An elongated slot 44 is formed in the blank to extend from the left hand end of crease 42 to the junction of creases 36, 41, thereby facilitating manipulation of the material in this zone. Panel 43 is provided with a generally rectangular handhold opening 45 adapted to register with the handhole opening in grip element 33, in the completed condition of the carrier.

The partition and suspending panel 43 has an over-all length of the same order as the combined vertical lengths of grip element 33 and side wall panel 18, so that when the carrier is completed it extends almost to the bottom thereof, thus affording full depth bottle protection. A diagonal crease 46 is formed in panel 43 adjacent the outer or right hand end thereof, this crease serving to define and hinge a bendable flap element 47 to the panel.

The carrier is completed from the blank 10 shown in Fig. 1 by the following sequence of operations: Adhesive is first applied to the triangular connecting members 40, 40' of the respective partition and suspending units 31, 32, and to the panels 43, 43' of those units, as indicated by stippling in Fig. 2. These panels and the associated connecting members 40, 40' are now folded about the respective creases 41, 41', as shown in Fig. 3, and in broken line in Fig. 2, causing connecting gussets 40, 40' to adhere to the triangular upper extensions 35, 35' of side wall panels 18, 14, respectively. The upper portions of panels 43, 43' are also adhered to the respective grip elements 33, 33', leaving the blank in the condition illustrated in Fig. 3 of the drawings.

Panels 23, 24, 25, 26 which are to constitute the automatic bottom of the carrier are now folded upwardly, inwardly and downwardly about the bottom-defining crease 22 and the glue laps 29, 30 of the respective panels 23, 25 are reversely folded about the respective creases 27, 28 and onto the associated panels.

After adhesive is applied to glue lap 30, the right hand end wall panel 16 and its associated bottom panel 26 are folded inwardly and downwardly about the crease 15, causing the flap 26 to be adhered to glue lap 30. The blank is now as shown in Fig. 4 of the drawings. Adhesive is next applied to the exposed upper surface of one of the partition and suspending panels, to bottom panel glue lap 29, and to marginal glue lap 20, as illustrated by stippling in Fig. 4, whereupon section 11 of the blank is folded upwardly, inwardly and downwardly about crease 19 onto section 12. This causes bottom panel glue lap 29 to be adhered to the bottom panel 24 and terminal glue lap 20 to be adhered to end wall panel

16. The partition and suspending panels 43, 43' are also adhered to one another, leaving the blank as illustrated in Fig. 5 in its completed, knocked-down, flat condition.

The carrier is erected to bottle receiving condition by applying compressive force to the opposite end margins of the knocked-down article, represented by the creases 19, 15. As this is done, the carrier approaches a rectangular cross section, viewed in plan as in Figs. 6 and 7. The opposite side wall panels 18, 14 shift outwardly in parallel relation and the adhesively connected bottom forming panels 23, 24, 25, 26 swing downwardly about their hinge line 22 and their respective hinge connections to one another, in well-known fashion. The opposite side wall bottom panels 23, 25 slide into a final position in which hook formations 49, 50 thereon are interlockingly engaged with one another, leaving the bottom in flat, horizontal condition.

Swinging movement of the bottom panels would normally be impeded by the partition panels 43, 43', which extend almost to the bottom of the carrier; however, the inclined creases 46, 46' enable the triangular flaps 47, 47' to yield outwardly in opposite directions, so that the bottom panels pass readily to their final locked position. The respective flap portions 47, 47' then return downwardly to vertical position under their inherent resiliency.

This leaves the two-ply partition and four-ply suspending or grip portion thereof in a vertical position, as illustrated in Fig. 7, so that bottles may be deposited in the carrier. The upright partition, overlying the interlocked hooks 49, 50 of the automatic bottom, resists upward impacts on the bottom tending to dislodge the panels therefrom of their interlocked relationship.

The carrier is extremely compact in character and is fabricated from a blank of minimum size. It is also a very sturdy carrier, by reason of the bracing action exerted on the side walls by the partition units 31, 32, as well as the characteristic longitudinal and transverse bracing action contributed by an automatically locking bottom construction.

I claim:

1. A collapsible paperboard carrier for bottles and like articles, comprising opposed pairs of side and end walls having bottom forming panels integrally hinged thereto, certain of said bottom forming panels being creased to define attaching means secured to other of the panels whereby to constitute an automatically interlocking bottom when the carrier is in erected condition, said bottom being upwardly disposed between said walls when the carrier is in a flat, knocked-down condition, and a partition unit on each of said side walls comprising a vertically extending panel integrally hinged by a vertical crease to an upper extension of the wall, a further partition panel, and a triangular connecting element integrally hinged by a diagonal crease to said upper extension and integrally hinged to said further partition panel by a vertical crease, said partition units extending substantially to the carrier bottom and at least one of said partition panels being provided with a diagonal crease adjacent the lower extremity thereof defining a bendable flap to accommodate movement of said bottom panels in being manipulated to locked condition.

2. A paperboard bottle carrier comprising pairs of side and end wall panels integrally connected to one another by vertical creases, each of said panels having a bottom forming panel integrally hinged by a horizontal crease to the lower margin thereof, certain of said panels being provided with diagonal creases defining bendable glue laps thereon and being connected to one another by said glue laps, each of said side walls being provided with an integral upper extension, a grip element integrally hinged by a vertical crease to each of said extensions and separated by a cut from the associated extension bearing side wall, a vertically elongated partition panel, and a connecting member integrally hinged to said last named panel and to said wall extension, the height of said partition panel approximating the combined vertical length of said

grip element and associated side wall panel, said partition panel being provided with a diagonal crease adjacent the lower end thereof.

3. A paperboard bottle carrier blank comprising pairs of side and end wall panels integrally connected to one another by vertical creases, each of said panels having a bottom forming panel integrally hinged by a horizontal crease to the lower margin thereof, certain of said panels being provided with diagonal creases defining bendable glue laps thereon, each of said side walls being provided with an integral upper extension, a grip panel integrally hinged by a vertical crease to at least one of said extensions and separated by a cut from the associated extension bearing side wall, a horizontally extending partition panel, and a connecting member integrally hinged to said wall extension and partition panel, the horizontal length of said partition panel approximating the combined vertical length of said grip element and associated side wall panel, said partition panel being provided with a diagonal crease adjacent the end thereof remote from said side wall extension.

4. A paperboard bottle carrier blank comprising pairs of side and end wall panels integrally connected to one another by vertical creases, each of said panels having a bottom forming panel integrally hinged by a horizontal crease to the lower margin thereof, certain of said panels being provided with diagonal creases defining bendable glue laps thereon, each of said side walls being provided with an integral upper extension, a grip panel integrally hinged by a vertical crease to at least one of said extensions and separated by a cut from the associated extension bearing side wall, a horizontally extending partition panel, and a connecting member integrally hinged by a horizontal crease to said partition panel and by a diagonal crease to said wall extension, the horizontal length of said partition panel approximating the combined vertical length of said grip element and associated side wall panel, said partition panel being provided with a diagonal crease adjacent the end thereof remote from said side wall extension.

5. A paperboard bottle carrier comprising pairs of side and end wall panels integrally connected to one another by vertical creases, each of said panels having a bottom forming panel integrally hinged by a horizontal crease to the lower margin thereof, certain of said bottom forming panels being provided with diagonal creases defining bendable glue laps thereon and being connected to one another by said glue laps, each of said side walls being provided with an integral upper extension, a grip element integrally hinged by a vertical crease to each of said extensions and separated by a cut from the associated extension bearing side wall, a vertically elongated partition panel, and a connecting member integrally hinged to said last named panel and to said wall extension, the height of said partition panel approximating the combined vertical length of said grip element and associated side wall panel.

6. A collapsible paperboard article carrier comprising opposed pairs of side and end walls having bottom forming panels integrally hinged thereto, certain of said bottom forming panels having a crease extending diagonally across one end thereof which defines an attaching portion which is secured to the adjoining panel whereby to constitute an automatically interlocking bottom when the carrier is in erected condition, said bottom forming panels being upwardly disposed between said side and end walls when the carrier is in a flat, knocked-down condition, and a cross partition unit hingedly connected to each of said opposed side walls, said cross partition unit comprising vertically extending partition panels integrally connected to each of said side walls along a vertical crease line and secured to each other in face engaging relation, at least one panel of said cross partition unit extending substantially below the connection thereof with the side wall to adjacent the bottom of the carrier and being provided with a diagonal crease adjacent the lower extremity thereof defining a bendable flap to permit downward movement of the bottom panels into bottom closing and locked condition when the carrier is in erected condition.

7. A blank for an article carrier which comprises a generally rectangular sheet of paperboard or like material which is cut and creased to provide a series of hingedly connected side and end wall forming panels which are separated by spaced crease lines extending transversely of the blank, bottom wall forming panels extending along one side edge of the blank which are separated from the side and end wall forming panels by a crease line extending longitudinally of the blank and which are freed from each other by cutting lines extending transversely of the blank, certain of said bottom wall forming panels having diagonal creases at one end thereof defining bendable glue laps thereon, and cross partition forming panels extending along the opposite side edge of said blank which cross partition forming panels are connected to the side wall forming panels by foldable connecting panels which are defined by longitudinally and diagonally extending crease lines, with the longitudinally extending crease lines defining one side edge of the cross partition panel.
